UNITED STATES PATENT OFFICE.

GEORGE F. ABENDSCHEIN AND ALBERT STAIB, OF NEW YORK, N. Y.

UPRIGHT-PIANO ACTION.

1,123,646.

Specification of Letters Patent.

Patented Jan. 5, 1915.

Application filed March 20, 1913. Serial No. 755,761.

To all whom it may concern:

Be it known that we, GEORGE F. ABENDSCHEIN and ALBERT STAIB, citizens of the United States, residing at New York city, in the county of New York, and State of New York, have invented certain new and useful Improvements in Upright-Piano Actions, of which the following is a specification.

10 Our invention relates to piano actions, particularly to certain improvements on the piano action illustrated in the application of George C. Snyder, filed on the 24th day of January, 1911, Serial No. 604,441.

15 The object of the invention is to improve upon the construction illustrated in the Snyder action by the provision of means whereby the hammer may be thrown outward from the strings after contact therewith and checked at different distances. In the construction illustrated in the said Snyder application, the hammer is caught positively upon its rebound from the strings and is always caught and held at the same distance 20 from the strings without regard to the amount of force or quality of the blow struck upon the keys.

25 A further object of the invention is to provide means whereby the form of catcher or back check illustrated in the said Snyder application may be used in connection with a jack tripped in the ordinary manner by a regulating button.

30 A further object of the invention is to prevent "trembling" or "stuttering" when the key is struck a relatively hard blow.

35 Other objects will appear in the course of the following description.

40 Our invention is illustrated in the accompanying drawings wherein:

Figure 1 is a side view of a piano action constructed in accordance with our invention with the parts at rest, the main rail, the tripping rail and the hammer rest rail being shown in section. Fig. 2 is a like view to Fig. 1 but showing the parts as they appear after the hammer has struck the string and rebounded after a light blow, and before release. Fig. 3 is a like figure to Figs. 45 1 and 2 but showing the parts of the action after the hammer has rebounded from the strings under the force of a heavy blow. Fig. 4 is a fragmentary side elevation of a piano action constructed in accordance with 50 my invention but showing the jack having an outwardly projecting tripping arm and

also showing a regulating rail of the ordinary type, the action rail and the regulating rail being in section.

Corresponding and like parts are referred to in the following description and indicated in all the views of the accompanying drawings by the same reference characters.

Referring to these drawings, 2 designates the action rail of an upright piano of any desired type, 3 being the wippen attached to the action rail by means of the wippen flange 4. Extending downward from the wippen is the usual abstract 5 which connects to the key in the ordinary manner. 55 Mounted upon the main rail 2 is a hammer-but 6 from which extends the shank 7 carrying the hammer 8 which is normally positioned away from the strings and rests upon the hammer rest rail 9. The hammer is impelled outward or away from the strings by the usual spring 10. All these parts except the hammer-but may be of any ordinary or usual construction but the hammer-but is constructed as will be later described to suit 60 the new structure.

As illustrated, the outer face of the hammer-but, that is, that part which faces away from the strings, is formed with an outwardly and upwardly projecting extension 65 or arm 11 which is bifurcated at its extremity for engagement with a reduced upper end of a catcher 12. The catcher is pivoted between the bifurcated extremity of the arm 11 by means of the pin 13. The upper end of the catcher is notched as at 14 and interposed between this notched upper end and a V-shaped pad 15 is a spring 16 which normally urges the upper end of the catcher outward. This V-shaped pad 15 is disposed at the junction of the upper face of the arm or extension 11 with the body of the hammer-but. Just below the ears 10^a which form the bifurcated portion of the extension 11 is disposed a pad 17 of 100 felt or other suitable material. The catcher 12 below the upper end thereof is formed with a perforation through which passes a limiting screw or stop 18 which bears at its inner end against the pad 17. The catcher 105 extends downward and outward and is then curved so as to extend downward and inward, that is, toward the strings of the instrument, and the inside face of its lower end carries buckskin 19.

Attached to the wippen 3 by means of the usual flange 20 is the jack 21. In Figs. 1.

2 and 3 this jack is shown as angular in form and as having a relatively long, upwardly extending arm 22 and a relatively short arm 23 extending inward toward the 5 action rail. As illustrated in Figs. 1, 2 and 3, the jack extends outward or away from the strings at its point of pivotal attachment to the flange 20, then extends upward and then extends inward and upward and 10 has an enlarged upper end or head 24. This head on its inside face is formed with a projection or tooth 25, and the outer face of the head is recessed as at 26 and the inner wall of this recess is upwardly and outwardly curved very slightly as at 27. Felt 28 is disposed against this inner wall 27, this felt having an outer surface which contacts with the adjacent surface of the skin 19 and the lower wall of the recess is protected by means of a strip of felt 29.

Just above the junction of the short arm 23 of the jack with the long arm 22, there is disposed a regulating finger 31. This finger is pivoted at 32 and has a rounded 25 inner extremity projecting beyond the jack and adapted to contact with a regulating rail. The finger 31 is adjusted upon its pivot by means of an adjusting screw 33. The regulating rail 34 is angular in cross 30 section and is held to the main rail by screws 35 or in any other suitable manner. The outwardly extending portion of the regulating rail has a downwardly extending beveled under face 36 upon which is disposed a felt 37 with which the regulating finger 31 is adapted to contact to trip the jack in a manner which will be apparent to those skilled in the art.

The lower face of the hammer-butt is provided with the usual shoulder 38 which is downwardly and rearwardly inclined and is slightly curved and is protected by buckskin 39 and felt 40. Below the shoulder the hammer-butt has a flat, downwardly extending face 41, and attached to the lower portion of this face on a line about even with the pivotal axis 42 of the hammer-butt is disposed an outwardly projecting block of felt 43 of such size that the bevel faced tooth 25 may be easily shifted into the space between the block 43 and the adjacent portion of the felt 39. Disposed between the felt block 43 and the felt 39 is a felt 44 having a downwardly and outwardly beveled face. The tooth 25 is so beveled that when at rest as shown in Fig. 1, one face of the tooth will rest against the beveled face of the felt 44 while the other face of the tooth will rest against the adjacent portion of the felt 39.

The hammer-butt is of course pivotally mounted as at 42 upon the usual hammer flange 45, and disposed between the under face of the short arm of the jack and the wippen is the usual jack spring 46, the wip-

pen being attached to the action rail by means of the flange 4 of the usual character.

The parts being constructed as described, the operation is as follows. Upon a depression of the outer end of the key, the abstract and the outer end of the wippen are raised. This lifts the jack bodily and with it the hammer until the tripping finger or regulating finger 31 strikes the felt pad 27 of the regulating rail. This occurs just before the hammer has struck the strings. As soon as the rounded face of the finger 31 contacts with the felt 37, the jack is turned upon its pivot and the upper end of the jack is thrown outward to the position shown in Fig. 2. At the same time that the upper end of the jack is moving outward or away from the strings, the hammer will rebound from the strings and the inner leather face 19 of the catcher 18 will come in contact with the rounded upwardly and outwardly extending face of the felt 28 which will frictionally resist the further rearward movement of the hammer. When a relatively light blow has been struck upon the key, the hammer will rebound to the position shown in Fig. 2 and be checked by the catcher. When, however, a relatively heavy blow is struck upon the key, the hammer will rebound farther as to the position 95 shown in Fig. 3 and it will be caught in the same manner by the catcher. It will be seen from Fig. 3 that upon this greater rebound of the hammer, the leather face 19 of the catcher will move farther down upon the 100 felted face 28 of the jack and that thus provision is made for the checking of either a very light blow or a very heavy blow without any tendency to catch the hammer at one point only, whether a heavy or a light 105 blow has been struck upon the key and thus cause trembling or stuttering.

It will also be seen that as the hammer moves back farther and farther before the release of the jack, there will be a slight wedging action between the felts 19 and 28 which will check the hammer but that this can not block the action for the reason that the catcher 12 is pivoted at 13 and is yieldable against the strength of the spring 16. It is to be particularly noted that with this construction, the position of the catcher 12 relative to the jack may be adjusted by adjusting the screw 18. By turning this screw inward, the lower end of the catcher will be 115 forced outward and by turning the screw reversely, the spring will force the lower end of the catcher inward.

It is a special feature of this invention that the catcher is capable of being rotated 120 outward, and that when thus rotated and the hammer turned upward, it is possible to draw the jack out entirely so that a screw-driver may be readily engaged with the screw holding the hammer-butt flange 45 in 130

place on the action rail, thus permitting the easy removal or replacement of a hammer-butt and hammer without the necessity of taking the action apart. Furthermore, as the catcher 12 is pivoted and is held in its proper position by means of the spring 16, it is obvious that it will be forced outward upon and over stroke of the key and a consequent greater outward movement of the upper end of the jack than normally occurs. The over stroke of the key may be caused by a number of different factors, as for instance the sagging of the keyboard or the flattening down of the key felts.

It is also to be particularly noted with regard to the mechanism illustrated in Figs. 1, 2 and 3 that no bridle tape is necessary, thus doing away with considerable expense and eliminating the danger of the bridle tapes being eaten away by mice, as very commonly happens. Furthermore, space is economized in this action which is particularly important where the action is to be used for player pianos and where even a very small fraction of an inch counts. Again in this form of action the necessity of constantly adjusting the regulating buttons as ordinarily found in piano actions is avoided. This necessity is due to the warping of the ordinary regulating button rail. The regulating rail 34 in our construction being attached firmly to the action rail can not warp and hence when the action has been once adjusted it remains adjusted. Inasmuch as when the jack descends, the tooth 25 engages the felt block 43, it will be obvious that the hammer will be retracted positively by the fall of the jack and will not have to be drawn back by any bridle tape. In order to secure a quick action of the hammer, however, it is also desirable to use the usual hammer spring 10.

In Fig. 4 we show our invention as applied to an action in which an ordinary regulating rail is used. In this figure, 48 designates the usual action rail of an upright piano, 49 the wippen, 50 the wippen flange, 51 the abstract, 52 the hammer-butt mounted upon the hammer-butt flange 53 and 54 the hammer shank. The hammer-butt is constructed in exactly the same manner as heretofore described, and is provided with the catcher 55 which has the same shape as that heretofore described and is provided with the regulating screw 56. The upper end of the catcher is engaged by the spring 57 which acts to force the lower end of the catcher inward to a degree limited by the stop screw 58. The jack 59 is pivoted at its lower end upon the jack flange 59 and is angular in form, the short arm 60 of the jack extending outward or away from the strings of the instrument instead of inward or toward the strings of the instrument, as in the jack shown in Fig. 2. The long arm

of the jack extends nearly vertically upward instead of inward and upward, as in the construction shown in Fig. 2, and the upper end of the jack is enlarged to form the head 61 provided with the rearwardly 70 and upwardly projecting tooth 62 and with the felt face 63 which is adapted to contact and have frictional engagement with the felt face 64 on the inner face of the lower end of the catcher. Disposed above the 75 short arm of the jack is a regulating rail 65 through which passes the usual regulating screw 66 carrying at its lower end a regulating button which is adapted to contact with the rounded upper edge face of the 80 short arm 60 of the jack.

It is to be observed that the rear face of the jack 21 as shown in Figs. 1, 2 and 3, is formed with a shoulder 67, which shoulder is adapted to engage with the projecting 85 flange of the regulating rail 34 in case the jack drops. The purpose of this shoulder is to prevent the jack from dropping down any farther than the shoulder will permit it when dropping upon the rail 34. Its main 90 function is, when the piano action is taken out of the piano, to hold the lower part of the action from falling out from the butt. The operation of this construction is, of course, apparent to those acquainted with 95 the art, and it will be seen that this form of hammer, jack and catcher permits the hammer to rebound to a degree corresponding to the stroke, and that by raising the catcher 55 the upper end of the jack may be moved 100 outward so as to permit the engagement of a screw-driver with the screw holding the hammer flange 53 in place, and further that this construction accommodates any over stroke.

With the action illustrated in Figs. 1, 2 and 3, a very high degree of repetition may be secured without, however, any trembling or stuttering when a heavy blow is struck upon the key while the advantages incident 110 to the construction illustrated in the aforesaid Snyder application are retained.

What we claim is:

1. An upright piano action including a hammer-butt, a jack having a head, the outer face of the head being upwardly and outwardly inclined, a bodily yieldable catcher carried by the butt and extending outwardly and downwardly over the head of the jack and having sliding engagement 115 with the outer face of the jack when in check, a spring acting to urge the lower end of the catcher toward the jack, and means limiting the inward movement of the lower end of the catcher under the action of the 120 spring.

2. An upright piano action including a hammer-butt having an upwardly and outwardly extended portion, a jack having an enlarged head at its upper end, said head 130

- having an upwardly and outwardly inclined outer face, and a catcher pivotally mounted on the extension of the butt and extending downward and outward over the head of the 5 jack, the inner face of the lower end of said catcher coacting with the outer face of the head and slidingly engaging therewith when the hammer is in check, a spring urging the lower end of the catcher toward the 10 jack, and an adjustable stop limiting the inward movement of the catcher under the influence of the spring and preventing the engagement of the catcher with the jack when the hammer is out of check.
- 15 3. An upright piano action including a hammer-butt having an upwardly and outwardly inclined shoulder and an upward and outward extension above the shoulder, said butt below the shoulder and spaced 20 therefrom carrying an outwardly projecting member, a catcher pivotally mounted upon the extension of the butt and extending downward and outward opposite to the shoulder, a spring yielding 25 resisting outward movement of the lower end of the catcher and a jack having a head at its upper end, the outer face of the head being formed to coact and having sliding engagement with the inner face of the 30 lower end of the catcher when the hammer is in check and the inside of the head being formed with a tooth adapted to engage between the shoulder and said projecting member at the lower end of the hammer- 35 butt.
4. In an upright piano action, an action rail, a wippen pivotally mounted thereon, a hammer-butt pivotally mounted upon the action rail and having a shoulder and being 40 upwardly and outwardly extended beyond said shoulder, said hammer-butt below the shoulder being formed with an outwardly projecting member spaced from the shoulder, a catcher pivoted to the upper end of 45 the extension of the hammer-butt and extending downward and outward, the lower end of the catcher being formed with an up-
- wardly and outwardly inclined face, a spring urging the lower end of the catcher inward, an adjustable stop for adjusting the 50 position of the catcher, a jack pivoted to the wippen and formed at its upper end with a tooth extending beneath the shoulder on the butt, the other face of the jack being inclined upward and outward and having 55 sliding engagement with the inner face of the lower end of the catcher when the hammer is in check.
5. In an upright piano action, an action rail, a wippen pivotally mounted thereon, a 60 hammer-butt pivotally mounted thereon, said hammer-butt being formed with a shoulder extending upward and away from the action rail, said shoulder being cushioned, said butt being also formed with an 65 upward and outward extension bifurcated at its end, a catcher pivoted in the bifurcated end of the extension and having a notched upper end, the catcher being curved downward and outward and then inward 70 toward the action rail, a spring disposed between the hammer-butt and the upper end of the catcher urging the lower end of the catcher inward, a regulating screw passing through the catcher and engaging the ex- 75 tremity of the extension of the hammer-butt, a jack pivotally mounted upon the wippen, the upper end of the jack being formed with a head having a tooth extending beneath the shoulder of the hammer- 80 butt, and an upwardly and outwardly inclined face coacting with the inner face of the lower end of the catcher and having sliding engagement therewith when the hammer is in check, said hammer-butt being 85 provided with a projecting felt block below the shoulder and spaced therefrom.

In testimony whereof we affix our signatures in presence of two witnesses.
